CARL H. DAVIS, OF NEW YORK, N. Y., ASSIGNOR TO TUBIZE CHATILLON CORPORATION, OF NEW YORK, N. Y., A CORPORATION OF DELAWARE

DESIGN FOR A TEXTILE FABRIC

Application filed January 23, 1931. Serial No. 38,424. Term of patent 3½ years.

To all whom it may concern:

Be it known that I, CARL H. DAVIS, a citizen of the United States, and a resident of New York, in the county of New York and State of New York, have invented the new, original, and ornamental Design for a Textile Fabric, of which the following is a specification.

Reference is had to the accompanying drawing, forming part thereof, wherein:—

The figure is a plan view of a piece of textile fabric showing my new design the portion within the dot-and-dash line showing one repeat.

I claim:

The ornamental design for a textile fabric substantially as shown and described.

CARL H. DAVIS.
